SPRAY WASHER

Flora H. Ellinger, Chicago, Ill., and Gustave S. Krantz, West Allis, Wis.; said Krantz assignor to said Ellinger

Application February 5, 1941, Serial No. 377,434

4 Claims. (Cl. 299—84)

This invention relates generally to improvements in the art of spraying liquid, and relates more specifically to improvements in the construction and operation of devices for producing shower sprays of soapy liquid or the like, for dish washing and analogous purposes.

An object of our invention is to provide an improved liquid spray washer, which is simple in construction and highly efficient in operation.

Many different types of portable spray heads have heretofore been proposed for the purpose of showering a fluent mixture of water and soap, either directly or through a brush, upon various objects such as dishes; and in at least one of the earlier assemblages of this type, it was proposed to admit the supply liquid pressure to the receptacle in which the auxiliary cleansing medium was confined, in order to produce the mixture and to deliver the latter to the spray nozzle or orifices. While some of these prior devices have been quite satisfactory, they were not adapted to effectively mix the soap with the fresh water so as to produce a uniform and mild mixture and to avoid waste of the cleansing medium, and they could not be used efficiently with either liquid soap, soap flakes or chips, or bar soap. These prior spray washers moreover could not be quickly and conveniently converted from soap mixture spraying to fresh water spraying, and vice versa, for washing and rinsing purposes, and therefore lacked considerable utility and flexibility in use. The previous spraying devices furthermore were not adapted to cause the mixture to foam and froth when it was delivered to the dishes or other objects being cleansed, and the prior spray washing appliances were defective and faulty in many respects.

It is therefore a more specific object of our present invention, to provide a new and useful portable washing and rinsing device for dishes or the like, which obviates all of the above-mentioned defects of the prior devices of this general type, and which is highly flexible and effective in use.

Another specific object of the present invention is to provide an improved portable spray washer adapted to be connected to any suitable source of liquid under pressure such as an ordinary faucet, and capable of producing a highly satisfactory mixture of soapy water when utilizing either liquid soap, chip or flake soap, plastic soap compounds, or bar soap.

A further specific object of the invention is to provide an improved soap dispensing spray head, of the type wherein the supply liquid pressure is utilized to force the cleansing medium from its confining chamber, and in which the mixture will be effectively produced and gradually dispensed and delivered in a most efficient manner.

Still another specific object of this invention

is to provide an improved portable dish spraying assemblage which is adapted to be quickly and effectively converted from a washing device capable of delivering a mixture of soap and water, into a rinsing device for discharging fresh water alone, and vice versa.

An additional specific object of our invention is to provide an improved household appliance especially adapted for washing and cleansing purposes, which may be utilized with utmost safety with various mediums including extremely hot water, and for diverse purposes; and which may be manufactured, sold and operated at moderate cost.

Another additional specific object of the invention is to provide a portable spray assemblage which can be readily manipulated, all parts of which are conveniently accessible for re-loading, adjustment, inspection and cleaning, which is durable and attractive in construction, and which will most effectively deliver the cleansing fluid against the dishes or other objects and convert the soap into suds.

These and other specific objects and advantages of our invention will be apparent from the following detailed description.

A clear conception of the several improved features constituting the present invention, and of the mode of constructing and of operating a portable spray washer built in accordance with the invention, may be had by referring to the drawings accompanying and forming a part of this specification, wherein like reference characters designate the same or similar parts in the various views.

Fig. 1 is an approximately central vertical section through an improved spray washer, showing the assemblage set for rinsing spray production, and also showing the flexible tubing for conducting fresh liquid to theh appliance;

Fig. 2 is a bottom view of the assemblage of Fig. 1, showing the improved spray slots and orifices;

Fig. 3 is a section through a fragment of the assemblage of Fig. 1, taken along the line 3—3 and showing the control valve and conduits, with the valve in neutral position;

Fig. 4 is a similar section showing the valve set for rinsing purposes only;

Fig. 5 is another similar section showing the control valve set for washing purposes;

Fig. 6 is another section similar to that of Fig. 1, taken through a modified spray washer;

Fig. 7 is a bottom view of the modified structure; and

Fig. 8 is a top view of the modified assemblage.

While the invention has been shown herein as being applied to portable spray washers especially adapted for dish cleansing purposes and utilizing soap as a cleansing medium, and supplied with

liquid by a rubber hose attachable to a faucet, it is not our desire or intent to thereby unnecessarily restrict the scope or utility of the improvement.

Referring to Figs. 1 to 5, the improved portable spray washer shown therein, comprises in general, a main casing 7 forming a cleanser or soap confining chamber 8, and having an open bottom; a spray head 9 associated with the casing 7 to provide a removable closure for the bottom; a manually operable control valve 10 adapted to deliver fresh water from a supply conduit 11, directly either to the chamber 8 through a port 12, or to the head 9 through a port 13; means such as a flap valve 14 for permitting escape of mixed fluid from the chamber 8 to the spray head 9 only when fluid pressure has been established within the soap confining chamber 8; an insulated handle 15 surrounding the conduit 11 for effecting manipulation of the casing 7 and spray head 9 as a unit; and a flexible conduit or hose 16 having one end secured to and communicating with the conduit 11, while its opposite end is provided with a fitting 17 formed for removable attachment to a faucet, or other source of supply of liquid such as hot water under pressure.

The casing 7 may be formed either of sheet metal with the aid of punches and dies, or as a die casting, or in any other manner, of light but durable metal, in order to reduce the weight thereof to a minimum; and while the entire bottom of the casing 7 may be opened for the insertion of a large bar of soap into the mixing chamber 8, the casing top may be provided with a removable cap 18 for effecting admission of liquid soap, or soap chips, without necessitating removal of the spray head 9. The spray head 9 may likewise be formed either of sheet metal, or as a die casting, or otherwise, of light material, and this head has an upper wall 19 which normally closes the bottom of the chamber 8, and a lower spray plate or diaphragm 20 spaced from the wall 19 to provide a spray chamber 21. The closure wall 19 has one or more openings therein which are normally closed by the flap valve or valves 14, and the valves 14 are riveted or otherwise secured to the wall 19 and may be formed of any suitable resilient material so that they will be opened more or less when pressure is established within the chamber 8. The peripheral portion of the spray head 9 may be provided with quick pitch screw threads 22 coating with similar internal threads on the casing 7, for effecting rapid attachment and detachment of these parts; and is also provided with a gripping flange 23, and with an annular liquid distributing groove 24 which communicates with the spray chamber 21 through a series of openings 25. The lower interior portion of the main casing 7 may also be provided with a flange 26, and sealing gaskets 27, 28, 29 may be inserted respectively, between the flange 23 and casing 7, between the flange 26 and spray head wall 19, and between the closure cap 18 and casing 7, in order to provide liquid tight seals.

The spray plate or diaphragm 20 of the spray head 9, is preferably dished slightly as shown in Fig. 1, and is provided with a multiplicity of small circular orifices 30, radial slots 31, and circumferential slots 32. The circular orifices 30 are adapted to deliver small circular jets from the spray chamber 21 normal to the diaphragm 20, and the slots 31, 32 are formed to deliver rather wide and flat fan shaped jets from the chamber 21 and diaphragm 20. These various types of

jets will cross and interfere with each other at the zone of washing, in a rather violent and turbulent manner, so as to cause the soap to froth and foam and thus form an abundance of soap suds, whenever a mixture of soap and water is being admitted to the chamber 21 and discharged therefrom. The circular orifices 30 may be punched in the diaphragm 20 in the ordinary manner, but the slots 31, 32 are preferably formed as shown in Fig. 1, by first slitting the diaphragm and by subsequently bending the metal on one side of each slit outwardly. This outward bending of the metal should not be too regular, as it is desirable to produce fan jets which will break up the adjacent jets and thus create the soap suds.

The fresh liquid supply conduit 11 is in the form of a rigid hollow tube firmly associated with a control valve housing 33 and extending upwardly and laterally away from the main casing 7. The insulating handle 15 cooperates with this tubular conduit 11 to provide a manipulating handle for the portable spraying device; and the fresh liquid supply hose 16 should be firmly attached to the projecting end of the conduit 11 with the aid of a cord or wire 34, and should be sufficiently flexible to permit unobstructed manipulation of the spray washer. The control valve housing 33 with which the tubular conduit 11 is rigidly associated, is also rigidly associated with the main casing 7, and the tapered control valve 10 is manually rotatable within the housing 33 with the aid of a handle 35 disposed near the main manipulating handle 15. The plug valve 35 is retained in place by a nut 36, and is provided with a limit stop pin 37 for preventing over-travel of the valve, and also has a central port 38 communicating with the conduit 11 and adapted to either be cut-off as in Fig. 3; or connected to the port 13 for fresh water rinsing purposes as in Fig. 4; or connected to the port 12 for washing purposes as in Fig. 5. The port 12 is constantly in communication with the soap confining chamber 8 which may be periodically supplied with either liquid, flake, or bar soap; and the port 13 is likewise in constant communication with the annular groove 24 as illustrated in Fig. 1.

While the normal use of the improved spray washer should be clearly apparent from the foregoing description of the construction thereof, a short resume of the operation will be given. When the confining chamber 8 of the casing 7 has been supplied with the desired kind of soap or other cleanser, and the fitting 17 has been connected to a suitable source of hot liquid or water supply under pressure, the spraying device may be moved about universally with the aid of the handle 15, and the valve 10 may be manipulated at will. If the valve 10 is set as in Fig. 3, no spray will be discharged from the orifices 30 and slots 31, 32, since the conduit 11 will then be shut-off. When the control valve 10 is shifted to the position shown in Fig. 4, the port 12 will be closed and fresh water under pressure will flow from the conduit 11 through the ports 38, 13, groove 24 and openings 25 into the spray chamber 21. This fresh liquid under pressure will maintain the valve 14 closed, and will flow through the spray orifices 30 and slots 31, 32, and may be used for rinsing purposes. When the control valve 10 is set in the position shown in Fig. 5, the port 13 will be sealed and fresh water will flow from the conduit 11 through the ports 38, 12 into the mixing chamber 8, and will fill this chamber with liquid under pressure which will thoroughly mix

with the soap. The liquid pressure will eventually force the fluid mixture through the opening in the wall 19 and past the flap valve 14 into the chamber 21, and from thence the soapy mixture will flow through the orifices 30 and slots 31, 32 in the form of jets which upon impinging with each other will produce foam or soap suds. The appliance may thus be used for washing purposes, but it may be quickly converted into a rinsing device, or the water supply may be cut off entirely.

Referring to Figs. 6, 7 and 8, the modified portable spray washer shown therein, comprises a main cup shaped casing 40 forming a soap or other cleanser confining chamber 41, and having an open top; a false bottom 42 confined in the lower portion of the casing 40 to form a spray chamber 43; a removable cover 44 having gun-lock lugs 45 cooperable with a mutilated flange 46 on the casing 40 to seal the chamber 41; a manually operable control valve 47 adapted to deliver fresh water from a supply conduit 48, directly either to the chamber 41 through a port 49, or to the spray chamber 43 through a port 50; a flap valve 51, or other means for permitting escape of mixed fluid from the upper chamber 41 to the lower chamber 43 only when liquid pressure is established in the chamber 41; an insulated handle 52 secured to the conduit 48; and a flexible liquid supply hose 16, not shown, but being attachable to the seruated outer end 53 of the conduit 48.

The casing 40 may also be formed of sheet metal, and the bottom of this casing is slightly dished and preferably has a multiplicity of orifices 54, radial slots 55, and circumferential slots 56. While the top of the casing 40 may be opened wide for the insertion of bar, flake or liquid soap, or other cleansing medium within the chamber 41, this open top may be sealed by the cap or cover 44, the lugs 45 of which are adapted to be passed through notches 57 in the flange 46 during application or removal of the cover. A sealing gasket 58 may also be provided in order to insure tight closure; and the rotary plug valve 47 is manipulable with the aid of a handle 59, so as to either admit fresh liquid under pressure to the chamber 41, or to the chamber 43, or to both of these chambers, in regulated quantities. The normal operation of the modified assemblage is quite similar to that of the spraying device of Figs. 1 to 5 inclusive, and will be obvious from the previous description.

From the foregoing detailed description it will be apparent that our present invention provides an improved portable spray washer, which is simple, compact and durable in construction, and which is moreover flexible and highly efficient in use. The improved device may be readily converted from washing with a soapy mixture to rinsing with fresh water, and vice versa, and is well adapted for use with various types of cleansing medium such as liquid soap, soap flakes or chips, plastic soap, or bar soap. The portable washing unit may be readily manipulated to produce the desired operation, and the insulating handles eliminate danger when operating with extremely hot liquid. The formation of the orifices and slots in the spray head, is extremely important, since the combined action of these orifices and slots produces a splashing and agitation

which is very effective, and reduces the soap consumption to a minimum. All parts of the spraying assemblage are readily accessible for adjustment, inspection, and cleaning; and both fluent soap and large bar soap may be readily introduced to the mixing chamber. The improved appliance is obviously neat appearing, sterilizes as well as washing, is easy to handle, and can be manufactured and sold at moderate cost; and the device has proven highly satisfactory in actual use.

It should be understood that it is not desired to limit this invention to the exact details of construction, or to the precise mode of use, herein shown and described, for various modifications within the scope of the claims may occur to persons skilled in the art.

We claim:

1. A spray device, comprising, a portable casing forming a soap confining chamber, a spray head having screw thread coaction with said casing and forming a detachable closure for said chamber and having a spray diaphragm provided with spray slots disposed at diverse angles relative to each other, means for admitting liquid under pressure to said chamber, and pressure operable valve means interposed between said chamber and said head for delivering liquid under pressure to said slots, said valve means being responsive to the pressure within said chamber.

2. A spray device, comprising, a portable casing forming a soap confining chamber open at the bottom and having a tubular insulated manipulating handle, a hollow spray head having screw thread coaction with said casing and forming a removable closure for said casing bottom and having a spray producing diaphragm provided with radial and circumferential slots, means for admitting liquid under pressure either to said chamber or to said spray head, and a pressure operated valve interposed between said chamber and said head for delivering soapy liquid under pressure to said slots, said valve being responsive to the pressure within said chamber.

3. A spray device, comprising, a casing forming a cleanser confining chamber, a spray head formed adjacent the bottom of said chamber, a partition wall between said chamber and said spray head, means for conveying liquid under pressure to said device, a valve operable to admit said liquid under pressure directly either to said chamber or to said spray head, and means suspended from said partition wall for admitting fluid from said chamber to said spray head only when pressure is established within said chamber.

55 4. A spray device, comprising, a casing forming a cleanser confining chamber, a spray head formed adjacent the bottom of said chamber, a partition wall between said chamber and said spray head provided with a passage, means for connecting said device to a source of liquid supply, a valve operable to direct liquid from said source of supply either to said chamber or to said spray head, and a resilient flap valve secured to said partition wall and normally covering said passage for conducting fluid from said chamber only when pressure is established within said chamber.
